UNITED STATES PATENT OFFICE.

LEMUEL B. DECKER, OF KENOGAMI, QUEBEC, CANADA.

APPARATUS AND PROCESS FOR GAS AND HEAT RECOVERY FROM DIGESTER BLOW-OFF EXHAUST VAPORS.

Application filed June 22, 1925. Serial No. 38,891.

To all whom it may concern:

Be it known that I, LEMUEL B. DECKER, a citizen of the United States, residing at Kenogami, Province of Quebec, Canada, have invented certain new and useful Improvements in Apparatus and Processes for Gas and Heat Recovery from Digester Blow-Off Exhaust Vapors; and I do hereby declare that the following is a full, clear, and exact description of the invention, such as will enable others skilled in the art to which it appertains to make and use the same.

The present invention pertains to a novel apparatus and process for gas and heat recovery from digester blow-off exhaust vapor in the cooking of wood pulp.

The object of the invention is to utilize the gas and heat present in the digester blow-off vapor produced in the cooking of wood pulp. This vapor is ordinarily discharged into the atmosphere, but in the present invention it is utilized by being led into a quantity of wood chips which are about to be cooked. In this manner, a saving is effected in the materials with which the chips are treated before cooking. After the exhaust vapor has been conducted to the chips, the latter are delivered to a digester where they are cooked in the usual manner. The vapor arising from this cooking is led to another batch of chips in the manner described.

The invention is fully disclosed in the following description and in the accompanying drawings.

The installation comprises a digester 1, and chip bin 2 arranged to communicate therewith, as by being in superposed relation, preferably within a housing 3. The tops of the digester 1 and chip bin 2 are provided with removable covers 4 and 5 for filling purposes as pointed out below. The lower end of the chip bin 2 is provided with a gate or slide 6, the outlet thus formed being in direct alinement with the upper end of digester 1. Outlet pipes 7 and 8 extend from the lower ends of digester 1 and chip bin 2 respectively, preferably passing through the housing 3.

Near the bottom of the housing and adjacent thereto is built a blowpit 9 into which the outlet pipe of digester 1 extends. The outlet 8 of the chip bin 2 is connected to the blowpit by means of a branch 10, the

pipes 8 and 10 being connected by means of a T 11. The pipes 7 and 8 are provided with valves 12 and 13 respectively.

A vacuum pump 14 is disposed at any convenient position and engages by means of a vacuum line 15 with the upper end of chip bin 2. This line contains a valve 16. Instead of the pump, a fan (not shown) may be placed in the line 8 between the T 11 and valve 13. The fan would be placed to draw from pipe 10 and blow towards the chip bin.

An exhaust pipe 17 is fitted into the remaining branch of the T 11 and is equipped with a valve 18.

The operation of the device is as follows:

The digester 1 is filled with chips and acid in the usual manner. The cover 5 is now removed from the chip bin 2, and this is filled also with chips. The cover 5 is now replaced upon the chip bin 2. Digester 1 is then cooked in the usual manner. Before blowing, the valves 16 and 13 are opened. Valve 18 is closed, the pump 14 is started, creating a vacuum from the top of blowpit 9, through branch 10, outer pipe 8, and through the chips contained in chip bin 2, and through the vacuum line 15.

The valve 12 beneath digester 1 is now opened, whereupon the contents is discharged into the blowpit. The vapor arising from the pulp is drawn along the course of the vacuum described above, acting on the dry chips contained in the chip bin 2 and is discharged through the vacuum pump 14.

When the digester 1 is finished blowing, the pump 14 is stopped. The cover 4 on digester 1 is now removed, slide 6 is pulled from the bottom of chip bin 2, and the contents of the latter dropped or conducted into the digester 1. The usual digesting process is now carried on in digester 1. The slide 6 is closed, valves 13 and 16 are closed, the cover 5 is removed from the top of chip bin 2, and the latter is filled with fresh chips in the usual manner. The process is continued in the manner described.

The exhaust 17 is used when the system is obstructed, as when under repair, or when the chip bin 2 is not being used. In such cases the valve 18 is opened and valve 13 is closed, and the exhaust vapor passes through pipe 17 into the atmosphere according to the usual manner of cooking.

The principle of the invention as thus described may be extended to an interrelated system of digesters and chip bins. The advantages of this process are as follows:

- 5 1. Uniform moisture in chips.
  2. Uniform temperature of chips.
  3. High increase in temperature of chips.
  4. Saving in steam due to the high temperature of the chips.
  - 10 5. Gas recovery.
  6. Better quality of pulp.
  7. A higher yield of pulp per digester.
- While a specific embodiment of the invention has been illustrated and described, it is
- 15 to be understood that various alterations in the details of construction may be made without departing from the spirit of the invention as indicated by the appended claims.

Having thus fully described the invention, what I claim as new and desire to protect by Letters Patent is:

- 20 1. A process for recovering gas and heat from digester blow-off exhaust vapor in the cooking of wood pulp consisting in conducting said vapor into a quantity of wood chips prior to cooking said chips.
- 25 2. A process for recovering gas and heat from digester blow-off exhaust vapor in the cooking of wood pulp consisting in conducting said vapor into a quantity of wood chips prior to cooking said chips, conducting said vapor treated chips into a digester, and cooking them in said digester.

3. A process for recovering gas and heat from digester blow-off exhaust vapor in the cooking of wood pulp consisting in conducting said vapor into a quantity of wood chips prior to cooking said chips, and conducting said vapor treated chips into said digester after the latter has been blown.

4. An apparatus for recovering gas and heat from digester blow-off vapor in the cooking of wood, comprising a digester having an exhaust and an inlet, a chip bin adapted to communicate with the digester inlet, and means for conducting vapor from the digester exhaust to said bin.

45 5. An apparatus for recovering gas and heat from digester blow-off vapor in the cooking of wood, comprising a digester having an exhaust and an inlet, a blowpit in communication with said exhaust, a chip bin adapted to communicate with the digester inlet, and means for conducting vapor from said pit to said bin.

55 6. An apparatus for recovering gas and heat from digester blow-off vapor in the cooking of wood, comprising a digester having an exhaust and an inlet, a blowpit in communication with said exhaust, a chip bin adapted to communicate with the digester inlet, a pipe connecting said pit to said bin, and means for drawing vapor through said pipe from the pit to the bin.

In witness whereof I have hereunto set my hand.

LEMUEL B. DECKER.
